PRODUCTION OF PHENOL BY OXIDATION
OF BENZENEGeorge Ghislain Joris, Convent, N. J., assignor
to Allied Chemical & Dye Corporation, New
York, N. Y., a corporation of New YorkNo Drawing. Application September 21, 1948,
Serial No. 50,429

9 Claims. (Cl. 260—621)

1

This invention relates to the oxidation of benzene to phenol by means of elementary oxygen and more particularly to the air oxidation of benzene in vapor phase to phenol.

It is known that passing benzene with a limited amount of air through a zone devoid of catalytic contact masses will yield phenol as a principal oxidation product. U. S. P. 2,223,383 of December 3, 1940, to Moyer and Klingelhoefer discloses processes of this sort. Such processes require rather high temperatures to effect appreciable outputs of phenol, for example temperatures from about 550° C. to 650° C.

Increasing the operating pressure for these processes above atmospheric has a tendency to lower the temperature requirement e. g. to about 400° C. at 100 atmospheres pressure; but equipment for operation at increased pressure is expensive and there is danger in operating a hydrocarbon oxidation process above atmospheric pressure because of the increased possibility of leaks from the equipment of poisonous, explosive vapors.

It has been proposed in order to lower the temperature required for air oxidation of benzene to phenol to employ impure benzene as the feed in excess over the benzene which will be oxidized in each reaction cycle and to withdraw excess purified benzene at the end of each cycle thus maintaining in the feed an appreciable concentration of impurities which serve to reduce the necessary operating temperature. However, the temperature reduction obtained in accordance with this proposal is only moderate: this method allows e. g. using a temperature of about 450° C. at 50 atmospheres pressure.

One object of my invention is to promote vapor phase air oxidation of benzene to phenol at pressures of the order of one atmosphere with output comparable to that of prior art processes at like pressures but at temperatures in the vicinity of 330°-350° C., which allows more accurate temperature control than in the prior art processes and reduces the severity of the conditions to which the oxidation equipment is subjected. Another object is to obtain improved yields of phenol on the aromatic hydrocarbon attacked as compared to the yields by prior art processes. Still another object is to obtain valuable co-products of oxidation along with the phenol. Other objects and advantages of my invention will appear hereinafter.

In accordance with my improvement in oxidation processes which operate at a pressure of the order of one atmosphere in the vapor phase to

2

convert benzene to phenol by action of elementary oxygen, a reaction temperature within the range of about 250°-400° C. is maintained in the reaction zone, and besides the benzene introduced in the reaction zone there is introduced into the reaction zone from about 1 to about 20 volumes per 100 volumes of benzene of at least one material of the group consisting of open chain hydrocarbons containing in the molecule at least one unbranched, saturated chain of at least 3 carbon atoms; cyclic saturated hydrocarbons containing at least 6 carbon atoms; and mixtures of normally liquid, non-aromatic hydrocarbons which mixtures contain at least about 25 percent by liquid volume of one or more of the aforesaid aliphatic or cyclic hydrocarbons. The promoter may be admixed with benzene, and this mixture may supply part or all of the benzene for my process.

20 By pressures of the order of 1 atmosphere I mean pressures between about 0.5 and about 5 atmospheres (absolute). Volume ratios given herein refer to volumes of the materials in the vapor state.

25 The introduction of the above materials in quantities within the specified ranges with total pressures of the order of 1 atmosphere results, I have found, in the appearance of a temperature range with lower limit about 250° C. and upper limit about 400° C. within which comparatively rapid oxidation of the aromatic hydrocarbon and the above foreign material occurs to form a phenol and products of incomplete oxidation of the foreign material plus some carbon oxides and other products. Below about 250° C. the reaction rate is small. The temperature of most rapid reaction and greatest phenol output per pass within the temperature range employed in my process is usually about 330°-350° C. Above about 330°-350° C. the reaction rate drops, more or less sharply depending on what promoter is used, on space velocity, as will be discussed below, and on promoter concentration. At temperatures above about 450° C. (i. e. above the temperature range of my process) the reaction rate once more rises with increasing temperature and at about 500° C. (in the presence of the promoters) oxidation of the reaction mixture again is rapid.

50 The promoter itself as well as the aromatic hydrocarbon is in part oxidized forming in addition to carbon oxides valuable compounds such as acetic acid and formaldehyde. These compounds can be separated from the other products and recovered.

Among the foreign materials suitable for incorporation as oxidation promoters in reaction mixtures according to my process are straight chain hydrocarbons such as normal pentane, normal hexane, normal heptane, normal octane, and normal decene-1; branched chain hydrocarbons such as 2-methylpentane; cyclic hydrocarbons such as methyl-cyclopentane, and cyclohexane and its homologs either pure or in mixtures such as gasolines high in naphthenic hydrocarbon content; and hydrocarbon mixtures, for example straight run gasolines, cracked gasolines and kerosene fractions, which mixtures contain substantial proportions of an open chain or a cyclic hydrocarbon promoter admixed with non-aromatic hydrocarbons, such as lower branched chain aliphatic hydrocarbons, themselves not necessarily good promoters. Apparently, the good promoters activate the poor ones in a hydrocarbon mixture such as a straight run gasoline, since such gasolines are as satisfactory as pure straight chain or cyclic hydrocarbons as promoters. Preferred promoters of the above group are those boiling within the range from about 30° C. to about 225° C., particularly about 70° C. to about 120° C.

The quantity of promoters present should be sufficient to bring about the oxidation of substantial amounts of benzene in one pass of the reaction mixture through the reaction zone. This requires a minimum of about 1 volume of promoter per 100 volumes of benzene in the reaction mixture. If the quantities of promoter present are small the quantity of phenol appearing in the liquid products of one pass depends linearly on the volumes of promoter introduced per 100 volumes of input benzene. For the oxidation of benzene to phenol with normal heptane as promoter, for example, this linear relation extends up to about 5 volumes of promoter per 95 volumes of benzene in the input gases. The curve continues upward, but less than linearly, above the 5:95 ratio. Preferred ratios, giving satisfactory production of phenol and low production of carbon oxides, are between about 5:100 and about 10:100. An input volume ratio of promoter:benzene of about 20:100 represents a suitable upper limit for promoter concentration in my process.

All of the promoters show in common the property of forming with air at temperatures in the range 250°-400° C. compounds containing oxygen which readily enter into oxidation reactions. These compounds apparently are peroxides. The promoters also show in common when pure the phenomenon of "cold flames" during their reaction with air in the temperature range 250°-400° C. That is, the promoter compounds when heated within this temperature range with suitable proportions of air produce in the reaction vessel, without much accompanying rise in temperature, a luminous glowing region. Actual ignition occurs only on sufficiently raising the temperature, increasing the pressure, or otherwise altering the reaction conditions.

I believe that the previously described low-temperature oxidation range from about 250°-400° C. within which my process operates is associated with peroxide formation from the foreign promoter material; and that the falling off in oxidation rate with increasing temperatures observed between about 350° C. and about 450° C. is associated with acceleration of processes in which decomposition of the peroxides is faster than their reaction with benzene. The high tem-

perature oxidation occurring from about 450° C. up appears due to a reaction distinct from that occurring in the temperature region below about 400° C., used in my process. However, I do not intend to limit the scope of my invention by this or any theory of my process.

With the less active promoters, use of pressures above atmospheric and up to 5 atmospheres may be desirable to promote formation of peroxides.

The following examples are to be understood as illustrative of the invention but not as limiting the scope of the invention.

Example 1.—A metered flow of air saturated with benzene by bubbling the air through a container of benzene maintained at constant temperature was mixed with a metered flow of normal heptane and passed down a heated Pyrex glass tube of 2" O. D. and 4' length at a space velocity of input gases and vapors (STP), based on the total volume of the tube, of 100 reciprocal hours. The first foot of the tube functioned as a preheater section. Temperatures were measured by a series of thermocouples down the tube. The temperature recorded below as reaction temperature is the temperature maintained in the hottest zone of the reactor. The exit gases were passed first through a trap at about 150° C. to remove tars, then through two scrubbing towers packed with stainless steel helices. The first tower was kept at about 50°-65° C. to condense some of the unreacted benzene which refluxed, removing phenol and other relatively involatile products from the product gases. This benzene solution of phenol was further concentrated by dripping into the head of a small packed column countercurrent to a flow of dry gas bled off from the exit gases.

The gases still containing some benzene entered the second scrubbing tower which was cooled with circulating ice water. An organic layer and an aqueous layer collected at the bottom of the tower; the organic layer was recirculated to the benzene evaporator.

The gases leaving the second tower were passed through charcoal traps to adsorb residual materials such as benzene; the gases leaving the charcoal traps were sampled for analysis regularly during the run and a portion was continuously collected for analysis by displacement of water in a storage bottle. The charcoal traps were periodically heated in a stream of nitrogen and the gas containing desorbed materials was passed to the benzene evaporator.

The quantities of all products collected were measured. The phenolic product was analyzed for phenol by bromination to tribromophenol. The aqueous products collected in the second tower were analyzed for acid and aldehyde content; and the organic products collected in the second tower and in the benzene saturator at the end of the run were analyzed for benzene and heptane by sulfonation of components other than benzene and heptane and measurement of refractive index of the unsulfonated residue.

The input volume ratio of air:benzene vapor in the above run was about 1; the input volume ratio of normal heptane:benzene vapors was 0.05; the reaction temperature was 340° C.; and the duration of the run was 31 hours.

The benzene attacked during the run per part by weight of phenol formed was about 1.2 parts representing about 2% of the total benzene circulated to the reaction zone during the reaction period. The normal heptane attacked on the

same basis was 2.0 parts and the oxygen consumed was 2.7 parts.

For 1 part of phenol obtained there were produced 1.7 parts of aqueous products, 0.50 part of tar, 0.55 part of sulfonatable material collected in the second tower and benzene saturator, 0.84 part of non-phenolic material collected with the phenol, 1.0 part of carbon monoxide and 0.23 part of carbon dioxide. The aqueous products contained considerable acetic acid and formaldehyde; the tar was mostly phenol-formaldehyde condensation product with small amounts of diphenyl, benzaldehyde and ortho-quinone.

The yield of phenol based on the benzene attacked represents 69% of theory and the carbon oxides formed represent only 18% of theory based on the benzene and the heptane attacked. N-hexane, n-pentane, and 2-methyl pentane when substituted for n-heptane in the procedure of this example likewise promoted the oxidation of benzene to phenol.

Example 2.—A series of runs was made at varying temperatures to test the effect of cyclohexane as a promoter. The reaction tube was a heated vertical 40 mm. O. D. Pyrex glass tube 25 70 cms. long. Metered flows of air, benzene and cyclohexane were introduced at the top of the tube. The upper part of the tube functioned as a preheater. Temperatures recorded as reaction temperatures are the temperatures maintained in the hottest zone of the reactor.

The product gases were passed through a Dry Ice trap to condense the liquid products and the non-condensable gases were analyzed for oxygen, carbon monoxide and carbon dioxide. Phenol was determined in the liquid products by bromination to tribromophenol.

With a space velocity of input gases and vapors (STP) of 150 reciprocal hours based on the total volume of the reaction tube, 5:1 volume ratio of air:hydrocarbons, and 1:19 volume ratio of cyclohexane:benzene in the input gases and at a reaction temperature of 333° C., 19% of the input oxygen was consumed and 1.8% by weight of phenol was found in the liquid products. The number of mols of carbon oxides formed by oxidation of the feed per mol of benzene in the feed oxidized to phenol was 6.1 mols. At a reaction temperature of 309° C. under conditions otherwise the same 9% of the input oxygen was consumed and 1.0% of phenol was found in the liquid products. The number of mols of carbon oxides formed per mol of benzene oxidized to phenol was 1.32. At 349° C. reaction temperature the percent oxygen consumption was 12% instead of 19% at 333° C. and the phenol found in the liquid products amounted to 1.4 weight percent instead of 1.8%. The number of mols of carbon oxides formed per mol of benzene oxidized to phenol was 4.44.

Similar results were obtained when instead of cyclohexane a gasoline containing large proportions of cyclohexane homologues was employed as promoter using the procedure of the above example. Methylcyclopentane employed similarly at temperatures about 340° C. and space velocities of about 100 per hour likewise promoted oxidation of benzene to phenol.

Example 3.—The apparatus used in this example was like that of Example 1 except that the reactor was a 3 inch inside diameter, 4 foot long aluminum pipe; and an additional scrubbing tower in which exit gases contacted water countercurrently was placed after the ice-water cooled scrubbing tower.

A run of 13 hours was carried out as in Example 1 but with a straight-run, debutanized, sulfuric acid treated Pennsylvania gasoline of boiling range 30° to 102° C. as promoter. This gasoline contained approximately 35% by liquid volume of straight-chain hydrocarbons, 31% by liquid volume of branched-chain aliphatic hydrocarbons and 34% by liquid volume of cycloparaffins. The volume ratio of air:hydrocarbon vapors was 1:1; the amount of the gasoline promoter contained in the benzene circulated to the reaction zone was about 5% by weight, and the temperature in the hottest zone of the reactor was about 330° C. The oxygen content of the exit gases, initially about 15% by volume, fell during about 7 hours to a value of about 10% by volume.

The results obtained are summarized in the following table in which the numerical values are per part by weight of phenol produced.

Benzene circulated to reaction zone: 27.1 parts

Consumed (parts):

Benzene	1.3
Gasoline	2.1
Oxygen	3.18
Total	6.58

Collected (parts):

Phenol	1.0
Tar	0.7
Formaldehyde	0.28
Acetaldehyde	0.17
Formic acid	0.1
Acetic acid	0.14
Carbon monoxide	1.16
Carbon dioxide	0.44
Water and other products	2.41
Total	6.4

Analysis for phenol was as tribromophenol; for total aldehydes was by the hydroxylamine method; for formaldehyde was by the colorimetric method using basis fuchsin indicator; for total acids was by titration with alkali using phenolphthalein indicator; and for formic acid was by treatment with mercuric oxide followed by standard acid titration.

Variables in my process such as ratio of air: hydrocarbon and space velocity may be within the ranges previously known for processes in which aromatic hydrocarbons are oxidized to phenols. Particularly suitable values for these variables are noted below.

Particularly suitable input volume ratios of air:vapors of organic reactants in my process are from about 5:1-1:5. Preferably a ratio of about 1:1 is employed since this ratio allows a satisfactory level of phenol output accompanied by a low value for the mols of carbon oxides produced per mol of phenol formed.

Space velocities of input gases and vapors (STP), based on the total volume of the reactor, of about 20 per hour and up are suitable for my process. Space velocities of about 75-300 per hour are especially suitable since these space velocities are conveniently obtained and lead to satisfactory levels of phenol output. A space velocity of about 100-150 per hour represents the preferred value in this range. The higher the space velocity, the greater is the output of phenol in unit time when the phenol outputs per pass are maintained. At high space velocities the peak for the curve of phenol output per pass vs. temperature becomes increasingly sharp; according-

ly at increasing space velocities increasingly accurate control of temperature is required to maintain temperatures about 340° C. at which maximum phenol output per pass is obtained.

The apparatus used to carry out my process may be constructed in accordance with previously known construction of apparatus for exothermic vapor phase oxidation processes employing as oxidizing agent a gas, such as air, containing elementary oxygen. The construction materials 10 may be chosen from those previously known for vapor phase air oxidation of aromatic hydrocarbons to phenols. Thus the reaction zone may be constructed of or lined with for example glass, boron oxide, or aluminum.

Preferably the apparatus provides for recycling unreacted benzene and promoter back to the reaction zone. The recycled material may contain partial oxidation products dissolved therein.

Preferably, provision is made for recovering other products, e. g. products obtained from the promoter, as well as for recovering phenol. For example, a water extraction of the crude phenolic product followed by benzene extraction of the aqueous phenol solution may be used to separate phenol from other products and to recover these products. The benzene solution of phenol resulting may then be distilled to recover pure phenol therefrom without substantial loss due to formation of tars during the distillation process.

I claim:

1. In the process for oxidizing benzene to phenol in vapor phase at pressures of the order of one atmosphere with elementary oxygen, the improvement which comprises introducing into the reaction zone benzene, oxygen and from 1 to 20 volumes (as vapor, per 100 volumes of benzene vapor introduced into the reaction zone) of at least one material of the group consisting of open chain hydrocarbons containing in the molecule at least one unbranched saturated chain of at least 3 carbon atoms; cyclic saturated hydrocarbons containing at least 6 carbon atoms; and mixtures of normally liquid, non-aromatic hydrocarbons which mixtures contain at least about 45 25% by liquid volume of hydrocarbon promoter aforesaid; and maintaining reaction temperatures in the hottest zone of the reactor in the range from 250° C. to 400° C.

2. A process in accordance with claim 1 in 50 which the space velocity of the input vapors

(STP) is at least about 20 volumes per hour per unit volume in the reactor.

3. A process in accordance with claim 1 in which the promoter material introduced with the benzene is a gasoline fraction.

4. A process in accordance with claim 1 in which phenol is separated from other products by a water extraction of the crude phenolic product followed by a benzene extraction of the resulting aqueous phenol solution.

5. A process in accordance with claim 1 in which the oxygen employed is oxygen of the air and the input volume ratio of air:organic re- 15 actants in vapor state is within the range 5:1-1:5.

6. A process in accordance with claim 5 in which the reaction temperatures are within the range of about 330°-350° C., the space velocities based on the total reactor volume, of the input gases and vapors under standard conditions are between about 75 and about 300 per hour, and the ratios of input promoter vapors:input benzene vapor are between about 5:100 and 10:100.

7. A process in accordance with claim 6 where- 20 in the promoter material boils within the range of about 70° C. to about 120° C.

8. A process in accordance with claim 6 in which the promoter material is a straight run gasoline fraction, the input volume ratio of air:hydrocarbons in vapor state is between about 1:1 and about 1:3, and the space velocity of the gases 25 and vapors is between about 100 and about 150 per hour.

9. A process in accordance with claim 6 in which the promoter material introduced with the benzene is a fraction containing a large proportion of cyclohexanes boiling within the range from about 70° to 120° C.
